UNITED STATES PATENT OFFICE.

JOSEPH SILVESTER, OF PITTSBURGH, PENNSYLVANIA, ASSIGNOR TO FORT PITT BEDDING COMPANY, OF PITTSBURGH, PENNSYLVANIA, A CORPORATION OF PENNSYLVANIA.

AUTOMOBILE-SEAT.

1,369,940.

Specification of Letters Patent.

Patented Mar. 1, 1921.

Application filed June 25, 1919. Serial No. 306,603.

To all whom it may concern:

Be it known that I, JOSEPH SILVESTER, a citizen of the United States, residing at Pittsburgh, in the county of Allegheny and State of Pennsylvania, have invented certain new and useful Improvements in Automobile-Seats, of which the following is a specification.

This invention relates to automobile seats, 10 and the like; and it comprises a frame provided with fastening elements each having a head, a projecting tongue having a slot therein, and a shank consisting of a pair of projecting prongs, said prongs passing 15 through openings in the covering, and one of the slots, with the head arranged upon the outer side of the frame, the tongue being bent around the frame, and the slot therein positioned to register with the slot in said frame, said prongs being passed 20 through said slot and then bent substantially at right angles; all as more fully herein-after set forth and as claimed.

The fastening element employed is a 25 button like member provided with a head which is arranged on the outer side of the frame work and which is provided with a pair of prongs adapted to be passed through openings in the inner and outer covering and through a slot in the frame. A laterally projecting tongue is arranged on the head of the fastening element and this tongue is adapted to be bent around the bottom of the frame and positioned with 30 its outer end against the back of the frame. The tongue is provided with a slot which registers with the slots in the frame when the tongue is in proper position. The prongs are passed through the slot in the tongue 35 and bent at right angles in opposite directions. These fastening elements are arranged at intervals around the frame, a sufficient member being employed to properly and securely fasten the covering. When the 40 seat is used for automobiles, motor boats and other constructions wherein the seat proper is arranged upon a wooden support, I find it advantageous to provide the projecting tongue or fastening element with a slight 45 offset at the point where it passes under the frame, when in position. This offset portion holds the seat spaced from the support and prevents the covering rubbing against the 50 support and wearing.

55 In the accompanying drawings I have

shown an advantageous embodiment of this invention. In this showing—

Figure 1 is a side elevation of an automobile seat, certain parts being broken away to show interior construction; 60

Fig. 2 is a vertical transverse sectional view through the frame and one of the fastening elements;

Fig. 3 is a horizontal sectional view on the line 3—3 of Fig. 2 and. 65

Fig. 4 is a detailed perspective view of the fastening element.

In the accompanying drawings, letter A designates generally the seat and the letter B the support upon which it is placed. The 70 seat consists of a frame 1 of metal or other suitable material provided with transverse cross bars 2. These cross bars are rigidly secured to the frame in any suitable manner. Coil springs 3 are mounted on the cross bars 75 and are held in position by tie wires 4 advantageously arranged at right angles to the cross bars. The tie wires pass over the lower coil of the spring, through an opening in the cross bars and then over the lower 80 coil of the spring on the opposite side of the cross bar. At the top of the coil spring, I provide two sets of tie wires 5 and 6. The ends of these wires are secured to suitable supporting means such as wire 7 spaced and 85 supported from the frame in any suitable manner. The two sets of upper tie wires are advantageously arranged at right angles to each other and are interwoven with each other and with the upper coil of the coil 90 spring as shown in Fig. 1. After the coil springs have been properly mounted a covering 8 of duck, canvas or the like is arranged over the springs and an outer covering of leather 9 is placed over the duck covering. These coverings are advantageously 95 cut the proper shape and size to cover the top of the seat and the side and end walls before being applied. The two covers are sewed together at the upper 100 edge of the seat on three sides as indicated at 10 in Fig. 1 and a filling of hair or felt, 11 is then placed between the two coverings. After the filling has been positioned the 105 coverings are sewed together on the fourth side and the filling is compressed to the desired degree.

The sections of the covering which extend down over the side and end walls of the seat are secured to the frame by fastening 110

elements C. The construction of the fastening element is shown in detail in Figs. 2 to 4 of the drawings. The frames are provided with slots 12 at suitable intervals and openings are arranged in the inner and outer covering adapted to register with the slots. The coverings are carried around the bottom of the frame and positioned along the back. The fastening element consists of a head or body portion in the form of a button 13 having a laterally projecting tongue 14. A second section having a head 15 is secured within the button 13 by crimping the edge of the button as indicated at 16. The head (15) is provided with a pair of prongs 17 and 18 which are passed through the openings in the covering and the slot in the frame. The projecting tongue is bent around the bottom of the frame and the outer end is arranged in position against the back of the frame. The tongue is provided with slot 19 which registers with the slot in the frame when the fastening element is in position. The prongs of the fastening element are passed through this slot and are then bent at right angles in opposite directions.

When the seat is employed as an automobile seat it is placed upon a frame of wood to permit its removal. This is the general construction of automobile seats in order that the space beneath the seat may be used for storing. In ordinary construction, the leather covering rubs against this wooden support and becomes worn. In order to prevent this, I provide an up-struck portion 20 in the tongue at the point where it passes around the bottom of the frame. When the seat is in position, the up-struck portions contact with the support B and hold the bottom of the frame spaced as shown in Figs. 1 and 2. This eliminates constant rubbing of the covering and the wear incidental to such rubbing.

The construction of the seat will be readily understood from the above description and the accompanying drawings. The method of supporting the springs is very simple and consists of very few parts decreasing the possibilities of the seat getting out of order incident to its use in an automobile. The fastening elements securely hold the coverings in position and cannot become loosened.

What I claim is:

1. In combination with an upholstered seat having a frame and a covering, the frame being provided with a number of slots and the covering being adapted to be placed around the frame, of a fastening device to secure said covering to said frame, said fastening device comprising a head, a prong arranged to pass through the slot in the frame, and a slotted tongue secured to the

head and arranged to be placed around the frame with its slot registering with the slot in the frame, said prong being passed 65 through the slot in the tongue, and bent against the frame.

2. In combination with an upholstered seat having a frame and a covering, the frame being provided with a number of slots 70 and the covering being adapted to be placed around the frame, of a fastening device to secure said covering to said frame, said fastening device comprising a head, a prong arranged to pass through the slot in the frame, and a slotted tongue secured to the 75 head and arranged to be placed around the frame with its slot registering with the slot in the frame, said prong being passed through the slot in the tongue, and bent 80 against the frame and an upstruck portion arranged in the tongue and adapted to be positioned beneath the bottom of the frame when the fastening device is in position.

3. In combination with an upholstered 85 seat having a frame and a covering, the frame being provided with a number of slots and the covering being adapted to be placed around the frame, of a fastening device to secure said covering to said frame, said fastening device comprising a body portion, a prong carried by the body portion and arranged to pass through the slot in the frame, and a slotted tongue secured to the body portion and arranged to be placed around the 95 frame with its slot registering with the slot in the frame, said prong being passed through the slot in the tongue, and bent back against the tongue clamping the same to the frame.

4. In combination with an upholstered seat having a frame and a covering, the frame being provided with a number of slots and the covering being adapted to be placed around the frame, of a fastening device to 105 secure said covering to the frame, said fastening device comprising a body portion, a prong carried by the body portion and arranged to pass through the slot in the frame, and a slotted tongue secured to the body portion and arranged to be placed around the frame with its slot registering with the slot in the frame, said prong being passed through the slot in the tongue and bent back against the tongue and clamping the same 115 against the frame, said tongue having an outwardly struck portion opposite the lower edge of the frame to form supports to prevent the covering from engaging the support upon which the seat rests.

In testimony whereof, I affix my signature hereto.

JOSEPH SILVESTER.
